(57) **CLAIM**

The ornamental design for a photograph or negative viewer, as shown and described.

DESCRIPTION

Utility patent application Ser. No. 11/506,679, filed concurrently with the present application, is related by subject matter.

FIG. 1 is an isometric view of a photograph or negative viewer; and,

FIG. 2 is a side view of FIG. 1.

The broken line showing is for environmental purposes only and forms no part of the claimed design.

1 Claim, 2 Drawing Sheets
